(57) **CLAIM**

We claim the ornamental design for a cartridge for continuous inkjet printer, as shown and described.

DESCRIPTION

FIG. 1 is a front view of a cartridge for a continuous inkjet printer showing the first embodiment of our new design; FIG. 2 is a rear view thereof; FIG. 3 is a top view thereof; FIG. 4 is a bottom view thereof; FIG. 5 is a right side view thereof; FIG. 6 is a left side view thereof; FIG. 7 is a perspective view as viewed from front and top direction thereof; FIG. 8 is a top view of the ROM holder alone as shown in FIGS. 1-7; FIG. 9 is a front view of the ROM holder alone as shown in FIGS. 1-7; FIG. 10 is a rear view of the ROM holder alone as shown in FIGS. 1-7; FIG. 11 is a perspective view of the ROM holder alone from the front and top direction thereof; FIG. 12 is a front view of a cartridge for a continuous inkjet printer showing the second embodiment of our new design; FIG. 13 is a rear view thereof of FIG. 12; FIG. 14 is a top view thereof of FIG. 12; FIG. 15 is a bottom view thereof of FIG. 12; FIG. 16 is a right side view thereof of FIG. 12; FIG. 17 is a left side view of FIG. 12; FIG. 18 is perspective view as viewed from front and top direction thereof of FIG. 12; FIG. 19 is a top view of the ROM holder alone as shown in FIGS. 12-18; and, FIG. 20 is a perspective view of the ROM holder alone from the front and top direction thereof as shown in FIGS. 12-18. The evenly dashed broken lines depict environmental subject matter and form no part of the claimed design. The (Continued)

dash-dot-dash broken lines represent the bounds of the claimed design and form no part of the claimed design.
